UNITED STATES PATENT OFFICE.

JOHN N. QUINN, OF CINCINNATI, OHIO.

AUTOMATIC SWITCH-THROWING DEVICE.

SPECIFICATION forming part of Letters Patent No. 702,745, dated June 17, 1902.

Application filed March 8, 1902. Serial No. 97,221. (No model.)

To all whom it may concern:

Be it known that I, JOHN N. QUINN, a citizen of the United States, residing at Cincinnati, in the county of Hamilton and State of 5 Ohio, have invented certain new and useful Improvements in Automatic Switch-Throwing Devices, of which the following is a specification.

The object of my invention is to provide an 10 attachment to a switch-stand with an operating lever-rod extended along the track adapted to be operated by a train, so as to secure an effectual closing of the siding-switch, thereby preventing a derailing of the train.

15 Another object of my invention is to so dispose the parts of said devices that the switch can be closed by the train while in motion when it is open or only partially open.

Another object of my invention is to so 20 combine the train-closing features with the switch-stand that the latter can be operated without disturbing the supplemental closing mechanism operated from the train some distance from the switch-stand.

25 Another object of my invention is to so arrange the train-operating devices with the switch-stand lever that when the switch-stand has been accidentally left open and then closed by the engineer on the train the switch- 30 stand cannot be operated to open the switch-rails without readjusting the connection between the two switch-throwing devices, thereby acting as a detective to show the delinquency of the switchman in not closing the 35 switch or else to show that it has been unlawfully opened.

Other features of my invention are more 40 fully set forth in the description of the accompanying drawings, forming a part of this specification, in which—

Figure 1 is a plan view of my switch-operating devices in position for use. Fig. 2 is an enlarged top plan view of the track-switch-operating mechanism. Fig. 3 is a section on line xx , Fig. 2. Fig. 4 is a perspective view of sliding frame. Fig. 5 is a perspective view of pivoted lever for operating the switch-bar. Fig. 6 is a perspective view of trip portion of tripping-arm. Fig. 7 is an enlarged section on line vv , Fig. 1. Fig. 8 is a perspective view of train-operated links and connecting-

rod, said parts being detached from each other.

In Fig. 1 of the accompanying drawings, A 55 A' represent the ordinary siding-switch rails closing to the main rails BB'. C represents the ordinary switch-stand; C', the switch-lever. D represents the switch-bar connected to the switch-rails. These parts are of ordinary construction.

60 My invention consists of interposing between the switch-bars D D' and the switch-stand what may be termed a "track-throwing" device. In the normal condition the switch-stand lever is connected to the switch-throwing mechanism, which also can be operated by the track-throwing mechanism. These intermediate throwing devices are composed of the following parts:

E represents a housing in which are mounted 70 the operating devices.

F represents a sliding frame adapted to move longitudinally in the housing or box.

a represents a sill on which is pivoted a lock-lever G. This lever is pivoted at its forward 75 end to the switch-bar and is the instrument which throws the switch-bar when it is operated by the switch-stand lever or by the track-throwing mechanism.

G' represents a locking-arm forming a part 80 of lever G and normally engaging a tenon connection with the switch-stand bar H. Said switch-stand bar when it is operated moves the lever G and throws the switch-bar D without affecting the track-operating mechanism 85 in the normal position of the parts. The switch-bar H rests upon the rail or sill b and held in position laterally by means of a guide c, affixed to the sill b. Between the sills a and b is a space I. (See Fig. 3.) In this 90 space is placed a trip-arm d, and this is detachably connected to the lever-arm G', preferably in the following manner:

e represents an open slot, its front face having a knife-edge point f. Upon the trip-arm d 95 is mounted a catch g, tapered rearwardly, as shown at h, so as to form an incline adapted to catch the knife-point f at varying distances and secure the engagement of the trip-arm d with the lever-arm G' either when the switch 100 is full open or only partially open. In Fig. 2 the parts are shown in the normal position.

The lever-arm G' extends back and is held from moving by the guard or ledge i back of the slot in the housing-box. In this position the switch is closed and the trip-bar d is not 5 in engagement with the switch-throwing arm. If now the switch-bar H has moved the arm G' forward far enough to pass free from the guard or ledge i , it is brought into position so as to engage with the catch h of the trip-bar d , operated by the track-throwing mechanism. The parts are so disposed that when the switch is partly open or full open this 10 engagement of the trip-bar d is positively secured by the movement of said trip-arm. In 15 order to hold the trip-bar back or to insure its engagement, a spring J is interposed between the sill a and said trip-bar. In order to prevent the trip-bar d from being thrown too far back, I provide stops j k , which arrest 20 the backward movement of the trip-bar beyond the desired position.

In order to hold the engagement of the switch-stand bar H with the lever-arm G' , I provide a spring G^2 , secured to the sill b and 25 the forward end engaging with arm G' , holding the parts in contact for the operation of the switch-stand.

In order that when the switch has been left accidentally open and is closed by the approaching train that this movement may be 30 detected or registered, I provide the following mechanism, so as to keep unshipped the switch-stand connection with the switch-bar, requiring a readjustment or connection of the 35 parts. This leaves the switch-rail permanently closed against opening. This is accomplished as follows:

K represents a catch pivoted to sill b . It is shown as provided with two teeth m . Upon 40 lever-arm G' is a tooth n . When the switch has been closed by the track-throwing mechanism, the parts will be in position shown in dotted lines, Fig. 2, the engagement of tooth n with the catch m holding the arm G' , and 45 consequently the arm G , in the locked position. The switch-bar opens and closes the switch by the longitudinal sliding of the frame within the housing. The track-throwing device closes the switch by the swing of 50 lever G solely. Consequently when the switch has been closed by the throwing of lever-arms G G' , with movement of the bed-frame, the arm G' will be locked backward, requiring a manual resetting of the parts before the 55 switch can be operated by the switch-stand. Thus an unlawful or an accidental opening of the switch by the switch-lever, which switch is closed by the train, will be detected or registered by locking the parts out of position until readjusted. It is preferred to 60 have the housing locked, so that it has to be opened by an authorized person, thus preventing unlawful tampering with the switch-stand and switch.

65 In order to operate the track-throwing mechanism from and on the moving train, I provide the following mechanism:

L represents a link-rod pivoted at one end to the trip-bar b and extending alongside of the track the required distance. The extended end is pivoted to a two-armed lever M , which is in turn pivoted at o to the bed O . 70

N represents a connecting-rod pivoted to the arm M' of the two-armed lever M ; N' , a coil-spring for holding it in its innermost position toward the track. The inner end of the connecting-rod is pivoted to link-bars P P' , each the counterpart of the other, the inner end of said connecting-rod being preferably housed within the links P P' . 75

p represents a slotted journal in which the pin of the connecting-rod moves laterally. These links P P' are placed alongside of the track at some predetermined height and distance, but in such relation with the moving train that their inner faces are engaged by a trip-lever projected down from the car or locomotive and in the path of the links, so as to engage them and press the said links outward, throwing the connecting-rod N outward, which in turn moves the two-armed lever and pulls the link L forward, which moves the lever-arms G G' in the housing-box, operating the switch-bar to close it completely, and whether the switch-stand be fully or partially open it would be closed by the approaching train in the manner hereinbefore described. I am thus able to obtain means for positively closing a switch whenever it is left open or partially opened, and thereby 85 preventing the derailing of the train, and when the locking-catches are employed the accidental or purposely leaving the switch open to the side track is detected and registered automatically by the train closing the 90 switch. 95

The two-armed lever M is shown in the preferred form of construction, the parts being arranged so that when the connecting-rod N is moved the pivot-point u will travel and 100 come to the dead-center line with pivot o , thereby limiting the movement of trip-bar L . By this means any desired distance of travel or throw of the link-bar L is obtained. If the switch-bar must be moved five inches or 105 three and one-half, the lever will be proportioned accordingly, so that it is limited to the distance of movement without regard to the distance the train has moved the links P P' . 110

Having described my invention, I claim— 115

1. A switch mechanism adapted to throw a switch-rail into or out of contact with the main rail, comprising a housing, a sliding frame therein movable to and from the track, a switch-lever, a bar connected thereto and to 120 the frame, a switch-bar connected to the switch-rail, pivotal connections between the last-named switch-bar and the sliding frame forming a break-joint by means of which the switch can be thrown independent of the sliding frame and mechanism for actuating the said break-joint, substantially as described. 130

2. A railroad-switch comprising a main rail and a switch-rail adapted to be moved into

- and out of contact therewith, a switch-lever, a sliding frame actuated thereby movable in a direction to and from the main rail, members pivoted on said sliding frame and connected to said switch-rail, rigid in a direction of movement of said sliding frame and movable in a direction transverse thereto, a trip device adapted to be actuated by the moving train, and connections between said trip device and one of said pivotal members mounted on said sliding frame whereby the switch can be closed independent of said switch-lever, substantially as specified.
3. A railroad-switch comprising a main rail and a switch-rail adapted to be moved into and out of contact therewith, a switch-lever, a sliding frame movable toward and from the main rail, a bar connecting said sliding frame to the switch-rail, a second bar connecting the said sliding frame to the switch-lever, pivotal connections on said sliding frame connecting said sliding frame to the bar attached to the switch-rail, said pivotal connections being rigid in a direction of movement of the said sliding frame and adapted to yield to a strain in a direction transverse thereto, to throw the switch-rail independent of the movement of the sliding frame, a trip device adapted to be actuated by the moving train, and connections between the said trip device and pivotal devices mounted on the sliding frame, whereby the switch can be closed independent of the position of said switch device, substantially as specified.
- 35 4. In combination with a railroad-switch and switch-stand operating a sliding frame to throw the switch, a switch-closing mechanism comprising a switch-bar, a lever pivoted thereto and to the sliding frame detachably connected to the switch-stand lever and a tripping mechanism adapted to engage said pivoted lever and connected to an actuated device alongside of the track in advance of the switch whereby said pivoted lever may be operated from the train to close the switch when partially or fully open, substantially as specified.
5. In combination with a switch-stand lever a sliding frame and a switch-bar, a lever pivoted to said sliding frame and to the switch-bar, and detachably connected with the switch-stand lever, a tripping mechanism detachably engaging with said pivoted lever and adapted to be operated independent of the switch-stand for closing the switch, substantially as specified.
6. In combination with a switch and switch-bar connected to an intermediate sliding frame of a lever pivoted to said sliding frame and to the switch-bar, mechanism for holding said pivoted lever into rigid position against the throwing strain of the switch-stand lever, substantially as specified.
7. The combination with a sliding frame forming the operating parts of a switch-stand of a lever pivoted to said sliding frame and detachably connected to the switch-stand lever, mechanism for holding said pivoted lever against movement on its pivot, a stop on the frame-bed for locking said lever in position when the switch is closed and tripping mechanism for releasing said lever when the switch is partially open and bringing into engagement a tripping mechanism whereby said lever can be thrown to close the switch by mechanism independent of the switch-stand, substantially as specified.
8. In combination with a sliding frame adapted to be operated by a switch-stand lever, of a switch-closing mechanism consisting of a lever pivoted to said sliding frame, an arm carrying a tripping device adapted to engage said lever when said sliding frame is moved forward, locking devices affixed to the pivoted lever and to the sliding frame with the parts so disposed that they will engage and lock said lever when the switch is closed, by said tripping-arm thereby requiring a resetting of said pivoted lever before said sliding frame can be operated, substantially as specified.
9. In combination with a switch-bar, a switch-stand and its operating-lever, of a sliding frame intermediate thereof, a lever pivoted to the sliding frame and to the switch-bar and detachably connected to the switch-stand lever, a tripping-arm intermediate of the parts of said sliding frame provided with means for engaging said pivoted lever and having connection with actuating mechanism independent of the switch-stand for operating said pivoted lever to close the switch, and mechanism for locking said lever in position after the switch has been closed by said tripping-arm, substantially as specified.
10. The combination with a switch-bar, a switch-stand and a sliding frame operated by the switch-stand lever, of a switch-closing lever pivoted to the said sliding frame and to the switch-bar, a tripping-arm adapted to be engaged with said pivoted lever, an extended rod connected to an actuated lever located alongside of the track and mechanism adjacent to said track connected to said actuating-lever adapted to be operated from a moving train and throw said lever on the sliding frame to close the switch, substantially as specified.
11. In combination with a sliding frame operated by a switch-stand lever, of a lever pivoted to said sliding frame and to the switch-bar, a tripping-arm operated by an actuating-lever located alongside of the track in front of the switch-stand, means located adjacent to the track for operating said actuating-lever whereby the switch may be closed by moving said actuating-lever independent of the switch-stand, substantially as specified.
12. A switch mechanism adapted to throw a switch-rail into or out of contact with the main rail comprising a housing, a sliding frame therein movable to and from the track, a switch-lever, a bar connected thereto and to the frame, a switch-bar connected to the

switch-rail, pivotal connections between said switch-bar and the sliding frame forming a break-joint by means of which the switch can be thrown independent of the sliding frame, 5 mechanism adapted to break said joint and close the switch, and locking means located in the housing adapted to be automatically engaged by one of said pivoted members when the joint is broken, whereby the switch is located in its closed position, substantially as described.

13. A switch mechanism adapted to throw a switch-rail into or out of contact with the main rail comprising a housing, a sliding 15 frame therein movable to and from the track, a switch-lever, a bar connected thereto and to the frame, a switch-bar connected to the switch-rail, pivotal connections between said switch-bar and the sliding frame forming a 20 break-joint by means of which the switch can be thrown independent of the sliding frame, mechanism adapted to break said joint and close the switch, and locking means located in the housing adapted to be automatically 25 engaged by one of said pivoted members when the joint is broken, whereby the switch is located in its closed position, and a slot in the side of said housing allowing a portion of one of the said pivoted members to project externally when the break-joint is operated thereby indicating that the joint has been broken, 30 substantially as described.

14. In combination with a switch-operating mechanism, an independent safety-trip there- 35 for, consisting of a base-plate located adjacent to the track, a lever pivoted to the base-plate opposing one of the tracks and adapted to be actuated by the moving train, a con-

necting-rod parallel to the track for transmitting motion to the switch-operating devices 40 and a bell-crank lever pivoted respectively to said base-plate, to said trip-lever and to said connecting-rod, the said bell-crank being shaped and fulcrumed so as to form a positive limit to the throw of the connecting- 45 rod, substantially as described.

15. In combination with a switch-operating mechanism, a bed-plate, a toggle-lever having its ends pivoted to the bed-plate and its middle joint flexed toward one of the track- 50 rails, means for holding said central joint normally in its position, the said central joint normally in this position, the said central joint forming an abutment adapted to be actuated by a moving train in a direction to 55 and from the rail, a connecting-rod leading from the bed-plate to the switch-operating mechanism, movable in a direction parallel to the track, a bell-crank lever the middle joint of which is pivoted to the bed-plate, one 60 of the ends of said bell-crank lever being pivoted to the end of the connecting-rod, and a link pivoted respectively to the other end of said bell-crank lever and to the said central joint of the toggle-lever, the said bell-crank 65 lever being shaped and fulcrumed to limit the length of throw of the connecting-rod irrespective of the length of throw of the said central joint of the toggle, substantially as described.

In testimony whereof I have hereunto set my hand.

JOHN N. QUINN.
